UNITED STATES PATENT OFFICE.

CHARLES H. MORAND, OF LOS ANGELES, CALIFORNIA.

FIRE-ESCAPE.

1,152,961.

Specification of Letters Patent.

Patented Sept. 7, 1915.

Application filed November 1, 1913. Serial No. 798,770.

To all whom it may concern:

Be it known that I, CHARLES HARRISON MORAND, a citizen of the United States, residing at Los Angeles, in the county of Los Angeles and State of California, have invented a new and useful Fire-Escape, of which the following is a specification.

Heretofore, in many instances, it has been found impossible to use my hinged form of folding fire-escape, embodied in Patent No. 1,069,975, granted August 12, 1913, on account of street wires, adjacent buildings and other obstructions that render insufficient the available space in which to operate the attachment.

An object of this invention is to minimize the amount of space required in which to operate a fire escape ladder of this character and to this end I provide a ladder having rails adapted to slide up and down to fold and unfold the steps of the ladder under a deck.

Another object is the provision of ladder-housing means to afford protection against snow, sleet and other inclemencies of severe weather.

Another feature is the provision of disengageable means whereby the entire fire-escape ladder may be drawn up into the housing without folding, said folding operation being very undesirable in cold weather where the sliding step is impracticable on account of the ice and snow.

Another object is to provide sprinkling means adapted to sprinkle the users of the fire-escape whenever fire breaks from the building and over the fire-escape decks.

This invention may be carried out in various forms without departing from the general scope thereof.

The accompanying drawings illustrate the invention.

Figure 1 is a broken front elevation of a fire-escape embodying the invention and mounted upon a building. Fig. 2 is a broken sectional elevation viewed from irregular line x^2-x^2 , Figs. 1 and 5. Dot-and-dash lines indicate parts of the ladder in a position assumed during the course of folding or unfolding. Fig. 3 is a view analogous to Fig. 2 showing the ladder in folded position. Fig. 4 is a broken sectional elevation showing the ladder in stored position in a housing. Fig. 5 is an enlarged broken fragmental plan section from line x^5 , Figs. 1, 2 and 6 illustrating the detachable guide

means. Fig. 6 is an enlarged broken fragmental elevation viewed from line x^6 , Figs. 2 and 5, the wall of the building being omitted. Fig. 7 is an enlarged sectional detail from line x^7 , Figs. 1, 2 and 4 showing a fragment of one of the sprinkling rails. Fig. 8 is a broken sectional elevation from line x^8 , Figs. 9 and 10 illustrating my sprinkling feature as applied to decks of an ordinary fire-escape. Fig. 9 is a broken fragmental plan view from line x^9 , Figs. 8 and 10. Fig. 10 is a broken front elevation showing one of the decks of Fig. 8 together with its sprinkling connections.

The folding ladder α of the fire-escape comprises side rails 1 having rollers 2 at their lower ends, said rails being mounted in slidable relation to a support 3 as the lower platform of a fire-escape deck 4 by means of guides 5 having elongated eyes 6 that are adapted to accommodate the side rails in a slanting position. Said guides are preferably made disengageable with the side rails and each consist of two members 7 and 8 pivotally mounted adjacent each other by studs 9 to a cross piece 10 of the support 3. Each of said members has a semi-elliptical opening 11 in one side thereof, these openings forming the elongated eye 6 when brought into register one with another as the members are turned together about the studs 9. Projecting lugs 12 at the free ends of the members are bored to receive a bolt 13 to securely hold said members together.

The metal steps 14 are arranged to run along the side rails 1 and are provided with the flexible connections 15 and 15' to support the steps, the upper step being detachably connected by connection 15' to each of the guide members 7 and the connections 15 extending between the front edge of each step and the rear edge of the next step below in succession so that as the side rails move into an aslant position in the guides 5, as shown in Fig. 2, the steps will run down along the side rails and come to rest properly spaced apart to form a stairway adapted to communicate with the deck 4 through the opening 16.

Hand rails 17 are hinged to standards 18 that are hinged to the side rails 1 and a flexible stay 19 connects each hand rail with its side rail to limit the movement of and hold said hand rails normal to the side rails when the latter are in an aslant position upon the ground. The side rails are spaced

apart by spacers 20, the bottom one of which engages the bottom step when the fire-escape is folded up as shown in Fig. 3 to thereby support the remaining steps beneath the guides 5.

A line 21 is attached to the upper ends of the side rails and has branch connections 22 extending to the hand rails, said line 21 being led upward and thence downward to a windlass device 23 fastened to the building wall 24. The windlass drum 25 is connected with the spur gear 26 driven by a pinion 27 meshing therewith and having a brake 28 and crank 29. A pin 30 slidable through the drum and seatable in a socket 31 in the base plate 32 affords means by which the drum may be locked from rotation.

When it is desired to fold the fire-escape ladder up the windlass will be turned to wind up the line, the connections 22 folding the hand rails up as the line becomes taut and said line then drawing the side rails from the aslant position to the upright position, shown by dot-and-dash lines in Fig. 2, and thence upward through the guides 6 and through the opening 16 in the platform 3, the bottom step meanwhile engaging the bottom spacer 20 to support the remaining steps as they are piled up by the continued upward movement of the side rails. When the side rails have been raised to the extended position shown in Fig. 3 with the steps folded thereon under the guides 5 the pin 30 is inserted through the drum into the socket 31 and the apparatus is then out of the way.

The ground adjacent the wall 24 to which the side rails are lowered preferably has a slight downward and outward slope so that as said side rails are gradually lowered by means of the brake 28 of the windlass, the rollers upon touching the ground will readily roll away from the wall and carry the rails and steps into an aslant position where they will be held ready for use by the elongated eyes 6, as shown in Fig. 2.

Eyes 33 are provided in the upper portions of the side rails to carry the detachable step connection 15' when disconnected from the members 7 of the guides to thereby support the steps when said guides are disengaged from the side rails preparatory to storing. A housing 34 (see Fig. 4) extending through an opening 35 in the second deck 36 is secured to the wall 24 in any suitable manner and is provided with line holes *b* in its top and an open mouth 37 at its lower end, said mouth being closed by a door 38 hinged at 39 and having a spring latch 40 to fasten said door over the mouth of the housing. This housing is provided for storage of the fire-escape ladder to afford protection against the inclemencies of severe weather. Said ladder is adapted to

be drawn up into the housing without folding by the line 21, upon opening the guides 5 to free the side rails after removing the bolts 13 and detaching the connection 15' therefrom and connecting to the eyes 33. 70

The guides may remain in this open position shown by dotted lines Fig. 5 during cold weather as, for instance, a whole winter season and in case of fire the stored ladder may be lowered first, onto the door 38 to 75 open the same and then on through the mouth of the housing directly to the ground where the rollers 2 will carry the side rails into an aslant position as the line 21 is played out. The pin 30 will be inserted 80 through the drum and into the socket 31 and the rails will then be supported by the line in position ready for use. Particular attention is directed to the combination with a platform 4 of a housing 34 having 85 an open mouth 37 at its lower end spaced apart from the platform, the shiftably mounted ladder *a* housed in the housing, the means as the lines 21 and their connections to lower and raise the ladder out of 90 and into said housing; said platform being constructed and arranged with relation to the housing so that in the lowered position said ladder will extend downward from said platform; a hinged door 38 for said open mouth below said housed ladder, said door being arranged to be swung down by gravitational force of said ladder as the same is lowered; and the spring latch 40 releasably holding said door against downward swinging from its own gravity but being releasable by pressure of the ladder against the door when said ladder is being lowered. I have made provision for complete protection of the ladder against the 105 weather and meddling interference, and at the same time have made provision for automatic discharge of the ladder from the housing immediately whenever any person manipulates the lowering means to lower 110 the ladder, said ladder being practically as free for use as though not housed. The side rails may be again drawn up into the housing without sliding the steps together if desired to store in cold weather, or the guides may be closed to engage the side rails preparatory to drawing the side rails up through the guides and folding the steps under the deck if desired to store in 115 warm weather.

It is thus seen that I have contrived a fire-escape suitable for both warm and cold weather, in which a ladder is provided having rails adapted to slide up and down to fold and unfold the steps of the ladder under a deck, as will be the case when the fire-escape is used in warm weather; and in which a ladder may be stored in a housing without folding where the folding operation is undesirable as will be the case 120 125 130

when the fire-escape is used in cold weather on account of the impracticability of the sliding steps when exposed to ice and snow.

Attention is now called to the novel means adapted to sprinkle the users of the fire-escape in case of need which comprises the pipe structure decks 4 and 36 secured to the wall 24 by straps 41 or otherwise, the top pipe rails 42 of which are provided with perforations 43 arranged along the inner sides thereof and the decks are connected together by pipe limbs 44 and connected to a water main 45 by a pipe 46 having a valve 47 therein to open and close the water communication to said decks above. In case of fire the valve may be opened admitting water to the pipe decks through pipe 46 and limbs 44, and the perforated top rails will then emit a spray out over the decks so that a person using the fire-escape will be enveloped in a fine falling spray. This sprinkling feature is especially desirable during the use of the fire-escape when fire breaks out through doors and windows, not shown, opening onto the decks. Although two decks only and a connecting ladder 48 therebetween are illustrated in the drawings it is to be understood that the novel sprinkling means may be embodied with any number of decks as requirements demand.

In Figs. 8, 9 and 10 an arrangement is shown whereby the sprinkling feature is applied to ordinary steel structure decks 48 and 49, each provided with the usual top rails 50 upon which are suitably mounted, as by straps 51, the perforated pipe rails 42' that are connected in a similar manner by limbs 44', pipe 46' and valve 47' with the main 45'.

40 I claim:

1. In a fire-escape, the combination with a support, of guides mounted on said support, side rails slidably mounted in the guides, and steps mounted to run on the rails and spaced apart to form a stairway when the side rails are lowered, said steps being adapted to slide together upon the side rails under said guides.

2. In a fire-escape, the combination of a support, guides mounted on said support and provided with elongated eyes, side rails slidably mounted through said eyes and adapted to be accommodated in a slanting position, and steps mounted to run on the side rails and spaced apart to form a stairway when the side rails are extended aslant, said steps being adapted to slide together upon the side rails under said guides.

3. In a fire-escape, the combination with a wall, of a support upon said wall, guides mounted on said support adjacent the wall, side rails mounted to slide in the guides and alongside said wall, and steps mounted to run on the side rails and spaced apart to form a stairway when the side rails are low-

ered, said steps being adapted to slide together upon the side rails under said guides when said side rails are drawn up through the support and alongside the wall to thereby allow the side rails only to extend up adjacent said wall.

4. In a fire-escape, the combination of a support, disengageable guides mounted on said support, side rails slidably mounted in said guides and steps mounted to run on the side rails, flexible connections between the steps, and a flexible connection detachably connected to said disengageable guides to support the topmost step when the side rails are in place therein.

5. In a fire-escape, the combination of a support, guide members pivotally mounted on said support, said members each having semi-elliptical openings adapted to register one with another to form elongated eyes, side rails slidably mounted through said eyes and adapted to be accommodated in a slanting position, steps mounted to run on the side rails, and flexible connections to carry the steps.

6. In a fire-escape, the combination with a support, of disengageable guides mounted on said support, said guides each comprising two members having semi-elliptical openings adapted to register with one another to form an elongated eye, side rails slidably mounted through said eyes and adapted to be accommodated in a slanting position, steps mounted to run on the side rails, and means to hold said members together with said semi-elliptical openings in register with one another.

7. In combination a platform, a housing having an open mouth at its lower end spaced apart from the platform, a shiftably mounted ladder housed in the housing, means to lower and raise the ladder out of and into said housing; said platform being constructed and arranged with relation to the housing, so that in the lowered position said ladder will extend downward from said platform; a hinged door for said open mouth below said housed ladder, said door being arranged to be swung downward by gravitational force of said ladder as the same is lowered; and a latch releasably holding said door against downward swinging from its own gravity, but being releasable by pressure of the ladder against the door when said ladder is being lowered.

8. In a fire-escape, the combination with a support, of disengageable guides mounted on said support, side rails slidably mounted in said guides and steps mounted to run on the side rails, flexible connections between the steps, a detachable connection adapted to be normally carried by the disengageable guides to support the topmost step, and eyes in the upper portion of the side rails to carry said detachable connection whenever

the side rails are disengaged from said guides for the purpose set forth.

9. In a fire-escape, the combination with a wall, of a support upon said wall, guides mounted on said support adjacent the wall, side rails slidably mounted in said guides and steps mounted on the side rails, hand rails foldable toward and from said side rails, a drum mounted upon said wall, a line between the drum and the side rails, branch connections of said line extending to the hand rails, and means to turn the

drum to wind the line to fold the hand rails as the line becomes taut and to then raise the side rails alongside said wall as the line is drawn up.

In testimony whereof, I have hereunto set my hand at Los Angeles, California, this 25th day of October, 1913.

CHARLES H. MORAND.
